CLAIM

The ornamental design for a triple server tray, as
shown, and described.

DESCRIPTION

FIG. 1 is a top plan view of a triple server tray showing
my new design;

FIG. 2 is a bottom plan view thereof;

FIG. 3 is an elevational view of the triple server tray
shown in FIG. 1, as viewed along any one of the three
directional arrows depicted in FIG. 1; and;

FIG. 4 is a sectional view as taken along line 4—4 in
FIG. 1.

FIG. 2

FIG. 4
